UNITED STATES PATENT OFFICE.

SAMUEL DENISON, OF FORT PLAIN, NEW YORK.

HYDROCARBON-BURNER.

SPECIFICATION forming part of Letters Patent No. 741,233, dated October 13, 1903.

Application filed December 30, 1902. Serial No. 137,168. (No model.)

To all whom it may concern:

Be it known that I, SAMUEL DENISON, a citizen of the United States, residing at Fort Plain, in the county of Montgomery and State of New York, have invented a certain new and useful Hydrocarbon-Burner, of which the following is a specification.

This invention relates generally to oil-burners, and more particularly to one adapted to be used in connection with hydrocarbon-furnaces, the object being to provide a simple and efficient construction whereby commingled oil and air may be injected into the fire chamber or box of a furnace.

15 Another object of the invention is to provide for atomizing or spraying the oil in very fine jets simultaneously with the commingling of the air therewith, whereby a more perfect combustion is obtained.

20 Another object of the invention is to provide for regulating the supply of air as circumstances may require.

With these and certain other objects in view the invention consists, essentially, in the 25 arrangement of an adjustable air-tube within a cylindrical shell, said shell being connected at its forward end to a ring which is attached to the front casing of the furnace, said ring being provided with means for regulating the 30 ingress of air to the burner at that point.

The invention consists also in providing an improved construction of atomizer adapted to be used in connection with an adjustable air-tube, said atomizer being arranged upon 35 the forward end of an air-pipe which extends through the rear end of the casing connected to the rear end of the cylindrical shell carrying the air-tube; and the invention consists also in certain other details of construction 40 and novelties of combination, all of which will be fully described hereinafter and pointed out in the claims.

In the drawings forming a part of this specification, Figure 1 is a perspective view of the 45 burner constructed in accordance with my invention. Fig. 2 is a vertical longitudinal sectional view of the same. Fig. 3 is an irregular sectional view taken on the line 3 3 of Fig. 2. Fig. 4 is a vertical sectional view 50 on the line 4 4 of Fig. 2. Fig. 5 is a top plan view partly in section and illustrating the construction of the atomizer. Fig. 6 is a lon-

gitudinal sectional view on the line 6 6 of Fig. 5. Fig. 7 is a detail perspective view of an atomizer, one corner being broken away 55 and more clearly illustrating the details of construction. Figs. 8, 9, and 10 show details of construction hereinafter described.

In carrying out my invention I employ a cylindrical shell A, which is connected at its forward end to a casting or ring B, said casting or ring being secured to the front casing of the furnace, the forward end of the casting projecting into the furnace, and the central opening of the ring or casting is enlarged or 65 extended toward the inner end, as most clearly shown at B'.

B² indicates a series of radially-arranged air-inlet ports extending obliquely from the exterior of the casting or ring and the central 70 portion of the same just to the rear of the expanded or bell-shaped opening. A band C surrounds the apertured portion of the casting or ring and is provided with a plurality of openings C², which are adapted to register 75 with the rear inlet-ports B² and by turning the band upon the ring it is obvious that the sides of the rear inlet-opening can be adjusted so as to permit more or less air, as required. The band C is preferably made angular or 80 flanged, and the vertical portion thereof is slotted, as shown at C', and a set-screw C³, working therethrough, serves to bind the band in its adjusted position. A casing D is secured to the rear end of the cylindrical shell 85 A, said casing having a depending neck D', which is made tapering at its lower end upon both the interior and exterior and is adapted to have an air-pipe connected therewith for the purpose of supplying air to the burner, 90 and in practice I prefer to have this air supplied by any suitable construction of blower. A valve D² is arranged within the neck D', said neck being provided with suitable flanges D³, arranged upon opposite sides of the neck 95 and above and below the stem D⁴ of the valve, said stem projecting through the neck D' at the rear and is provided with a hand-wheel D⁵, by means of which it is turned. This valve is adapted to regulate the supply of air 100 into the interior of the burner, and in order that various adjustments of the valve may be had I provide a disk D⁶, which is movable longitudinally upon the valve-stem, but turns

therewith, said disk having a pin D⁷, which is adapted to engage one of the series of recesses D⁸, produced in the contiguous base of the neck D', so that when the pin is in engagement with one of these recesses the valve will be locked in position.

A coil-spring D⁹ surrounds the valve-stem between the disk and hand-wheel D⁵, and the disk is constructed with suitable wings D¹⁰ to facilitate the manipulation of said disk, as it is obvious that in order to adjust the valve it is necessary to disengage the pin from this recess, and this is accomplished by sliding the disk upon the valve-stem, comprising the spring D⁵, which normally holds the pin in engagement with the recess.

The flanges D⁸, before referred to, act as stops to limit the movements of the valve and hold it in an entirely closed position. An air-tube E is arranged centrally and longitudinally within the cylindrical shell, the forward end of the air-tube resting within the central opening of the casting-ring, as most clearly shown in Fig. 2. The rear end of the air-tube is considerably enlarged and is supported and held in its proper position by means of inwardly-extending lugs E', carried by the casting D.

A ring F is arranged within the casting-ring B between the said ring and the forward end of the cylindrical shell A, said ring encircling the forward end of the air-tube E, and in order to steady the movement of the said air-tube I prefer to construct the same with a rib E², which works in a slot F², produced in the ring F. This ring is provided with a series of openings F', through which air can pass when the air-tube is moved rearwardly, said rearward movements of the air-tube being accomplished through the medium of a toothed rocking lever G, which engages the rack-teeth G', formed upon the under side of the air-tube E, said toothed rocking lever having an operating-handle G² arranged upon the interior of the burner.

From the above description it is obvious that air entering the casing D will pass through the air-tube E and also around the same. When the air-tube is in the position shown in Fig. 2, the air can only pass through the said tube, inasmuch as the forward end of the tube fitting the central opening of the casting-ring prevents the escape of the air around the tube; but the moment the tube is moved rearwardly through the medium of the hand-lever G² and toothed rocking lever G the air will pass through the openings F and around the forward end of the rear tube, as well as through the air-tube, thereby supplying an additional quantity of air whenever occasion requires it, and if this is not enough to support combustion in the complete manner it is desired the band C can be adjusted so as to open the air-inlet ports B², and an additional quantity of air will be supplied to the burner. The oil-pipe H passes through a cap H', secured upon the casing D at the rear end, said

oil-pipe being connected at its rear end to the valve-casing I, having a needle-valve I' arranged therein, and this valve-casing I has a depending portion I², to which a swinging connection I³ is attached, said swinging connection I³ being connected in any suitable manner with a supply-pipe, and in practice I prefer to have a flexible connection between the swinging connection and the supply-pipe, so that, if desired, the oil-pipe H may be withdrawn from the burner by removing the cap H' and drawing the pipe H out rearwardly. The pipe H is normally held locked by means of a set-screw H², passing through the cap H' and binding upon the oil-pipe. This oil-pipe H passes centrally through the casing D and projects a suitable distance into the air-tube E and supplies oil to the atomizer K, so that the oil is minutely subdivided simultaneously with its being commingled with the air. The atomizer K is secured upon the forward end of the oil-pipe and comprises a box-like portion K', having an inlet-opening K², through which the oil enters. This opening K² discharges into a transverse trough K³, from which lead a series of channels K⁴, said channels leading directly to a series of openings K⁵, produced in the forward end of the pan and to which are connected the atomizer-nozzles K⁶, which are in the form of fine pipes or jets, said nozzles being arranged at oblique angles and preferably pointed alternately upwardly and downwardly, as most clearly shown in Figs. 2, 6, and 7. The forward portion of the pan is constructed with a hood K⁷, which serves to collect a certain portion of air which is utilized in forcing the oil through the atomizer-nozzles, and by means of an atomizer constructed as herein shown and described I am enabled to divide and break the stream of oil into a series of fine jets or sprays, which can be intimately commingled with the air and fed into the furnace through the bell-shaped opening of the casting-ring. By adjusting the oil-pipe the atomizer can be adjusted to any desired or proper angle. It will of course be understood that the trough K³ and channels K⁴ are formed in the bottom of the pan, and the atomizer will of course be constructed of material suitable to withstand the heat to which the furnace will be subjected.

It will thus be seen that I provide a simple and efficient construction of hydrocarbon-burner by means of which oil in a finely-divided state can be commingled with the proper amount of air and injected into a furnace, thereby producing complete combustion and an intense heat.

Having thus fully described my invention, what I claim as new, and desire to secure by Letters Patent of the United States, is—

1. An oil-burner of the kind described comprising a shell, a casing secured to said shell, an air-tube slidably resting in the shell and having rack-teeth formed on its exterior surface, a toothed rocking lever adapted to en-

gage said teeth, an oil-pipe extending into said air-tube, an atomizer comprising a plurality of obliquely-arranged pipes, secured to the inner end of the oil-pipe, means for leading oil to said pipe, and means for supplying air to the air-tube.

2. In an oil-burner of the kind described an atomizer carried by the oil-pipe, said atomizer consisting of a pan having an opening through which the oil enters, a transverse trough, a plurality of longitudinal channels and a series of nozzle tubes or pipes extending from the pan and communicating with the forward end of the channels, as specified.

15 3. In an oil-burner of the kind described, an atomizer adapted to be arranged upon the forward end of the oil-pipe said atomizer consisting of a pan having an opening in the rear end thereof and through which the oil enters, a transverse trough, a series of longitudinal channels, a series of nozzle tubes or pipes arranged alternately at oblique angles and the shell or hood arranged at the forward end of the pan as specified.

25 4. In an oil-burner of the kind described

the combination with the casting-ring having the air-inlet ports and perforated band encircling the said casting ring and tube and regulating the passage of air through the ports, of a shell connected to the casting-ring 30 and air-tube arranged within the shell and means for moving the said air-tube longitudinally, a ring surrounding the air-tube and arranged between the forward end of the shell and the casting-ring, said ring having a series 35 of openings produced therein, the casing connected to the rear end of the shell and having a dependent neck, an air-valve arranged in said neck and provided with means for regulating the same, the oil-pipe passing through 40 the casing through the rear end and projecting into the air-tube and oil-regulating valve and casing connected with the rear end of the oil-pipe, and the atomizer arranged upon the forward end of said pipe, substantially as 45 specified.
